PAPER FASTENER OR THE LIKE

Renato Crotti, c/o Silan S.a.S., Via Provinciale 45, Carpi, Modena, and Aurelio La Viola, Via General Fara 20, Milan, Italy

Filed Mar. 8, 1967, Ser. No. 6,131

Claims priority, application Italy, Oct. 29, 1966

Term of patent 14 years

Int. Cl. D8—02; D19—02

U.S. Cl. D74—1

FIG. 2

FIG. 4

FIG. 1 is a side view of a paper fastener or the like, showing our design, the side opposite thereto being similar in appearance;

FIG. 2 is a front view;

FIG. 3 is a rear view; and

FIG. 4 is a top view thereof.

We claim:

The ornamental design for a paper fastener or the like, substantially as shown and described.
